[57] CLAIM

The ornamental design for a fingernail clipper, as shown and described.

DESCRIPTION

FIG. 1: is a front perspective view of the clipper;
FIG. 2: is a right side elevational view of the clipper;
FIG. 3: is a left side elevational view of the clipper;
FIG. 4: is a top plan view of the clipper;
FIG. 5: is a bottom plan view of the clipper;
FIG. 6: is a front elevational view of the clipper; and,
FIG. 7: is a back elevational view of the clipper.
The undisclosed and partially obscured surfaces of the design follow the contours of the portions visible.
